DESIGN FOR A SHOE

Joseph Mascali, New York, N. Y.

Application December 18, 1935, Serial No. 60,154

Term of patent 3½ years

To all whom it may concern:

Be it known that I, Joseph Mascali, a citizen of the United States and resident of New York city, in the county of Kings and State of New York, have invented a new, original and ornamental Design for a Shoe, of which the following is a specification, reference being had to the accompanying drawing, forming part thereof, in which,

Fig. 1 is a plan view of the shoe showing my new design;

Fig. 2 is a side view of the shoe shown in Fig. 1, and

Fig. 3 a rear view of the shoe showing the design carried out on the heel.

I claim:

The ornamental design for a shoe as shown.
Dated, December 16, 1935.

JOSEPH MASCALI.
